J. Greer & Co.
Design for a Stove

Patented May 15, 1860.

Dec 1242

James Greer & Rufus J. King, of Dayton, Ohio.
Letters Patent No 1242 dated May 15 1860.

The schedule referred to in these Letters Patent and making part of the same.

To all whom it may concern:

Be it known that we James Greer and Rufus J. King, both of Dayton Montgomery County Ohio, have invented a certain Ornamental design for Stoves, and we hereby declare the same to be clearly set forth in the accompanying drawings, making part of this specification in which

We claim as new and of our invention herein and desire to secure by letters patent.

The ornamental design for Stoves, exhibited in the accompanying drawings

In testimony of which Invention We hereunto set our hands
